UNITED STATES PATENT OFFICE

135,770

DESIGN FOR A CANDY BOX

Eugene B. Rice, Denver, Colo.

Application August 8, 1942, Serial No. 107,848

Term of patent 7 years

To all whom it may concern:

Be it known that I, Eugene B. Rice, a citizen of the United States, residing at the city and county of Denver and State of Colorado, have invented a new, original, and ornamental Design for Candy Boxes, of which the following is a specification, reference being had to the accompanying drawing, forming a part thereof.

In the drawing

The characterizing feature of my design for the box shown resides in the specific flanges surrounding the side wall at the bottom and top as illustrated in Figure 1 of the drawing.

I claim:

The ornamental design for a candy box, as shown and described.

EUGENE B. RICE.
